WATERPROOF WALL PLATE WITH HINGED LIDS

Paul H. Winter, Syracuse, N. Y., assignor to Pass & Seymour, Inc., Syracuse, N. Y., a corporation of New York

Application February 14, 1957, Serial No. 640,128

10 Claims. (Cl. 220—24.3)

This invention relates to wall plates for outlet receptacles and more particularly to such plates with a hinged lid over each opening therethrough equipped if desired to provide waterproof closure therefor.

It is a general object of the present invention to provide novel and improved wall plates with hinged lids.

More specifically it is an object of the present invention to provide wall plates with hinged and spring closed lids in which all hinge parts are formed without drilling or other machining and assembled without the use of loose pins, rivets and the like.

An important object of the invention consists in the formation of half bearings integral with the plate and trunnions integral with the lid and held in assembled relationship by a sheet metal hinge and spring cover interlocked with the plate by integral parts.

Another important object of the invention resides in the arrangement of hinge trunnions of different lengths whereby one may be surrounded by the lid closure spring beyond its cooperation with the half bearings.

One pertinent feature of the invention consists in arranging spacer means between the half bearings to hold the lid against lateral movement by engagement with the ends of the trunnions.

Another pertinent feature involves the disposition of the helical spring so that one end is engaged on the plate edge and hidden by the plate extension which interlocks with the spring cover.

Another important feature is the construction of the parts wholly without machining, drilling, riveting and the like whereby the cost is materially reduced without impairing the quality.

Still another important feature consists in the use of the pressed metal hinge and spring cover which holds the trunnions in the half bearings, has integral attaching means thereon for mounting on the plate and provides stops to limit the extent of lid lift.

Other and further features and objects of the invention will be more apparent to those skilled in the art upon a consideration of the accompanying drawing and following specification wherein is disclosed a single exemplary embodiment thereof with the understanding that such changes and modifications may be made therein as fall within the scope of the appended claims without departing from the spirit of the invention.

In said drawings:

Fig. 1 is a face view of a waterproof wall plate with hinged lids, the whole being constructed in accordance with the present invention and showing one lid closed and one open;

Fig. 2 is a fragmentary face view of the wall plate showing only the integral parts thereof;

Fig. 3 is a fragmentary section taken on broken line 3—3 of Fig. 2 showing a trunnion socket;

Fig. 4 is a transverse section taken on broken line 4—4 of Fig. 1 showing the spring held cover in closed position;

Fig. 5 is a left end view of the device of Fig. 1;

2

Fig. 6 is a top plan view of the device of Fig. 1 showing the lids both closed;

Fig. 7 is a perspective view of the pressed metal hinge and spring cover before application to the wall plate;

Fig. 8 is a view of the left portion of Fig. 1 with the spring cover in section on line 8—8 of Fig. 5;

Fig. 9 is a fragmentary right end view of the wall plate illustrating the hinge and spring arrangement and the function of the cover element; and

Fig. 10 is a rear elevation of the face plate and assembled parts.

Heretofore a waterproof wall plate for electric convenience outlets has been provided with a screw-threaded and gasketed cap for screwing onto a spigot sticking out from the face of the wall plate and surrounding the opening for the convenience outlet, or in certain other cases has a hinged lid carrying a gasket or cooperating with one on the plate and held closed by a spring or the like. Such constructions involved considerable machine work or a rather intricate hinging mechanism for attaching the lid to the wall plate and required the use of separate hinge pins, screws or rivets for fastening the stationary hinge portion to the wall plate and altogether required the manufacturing and assembling of more parts than are necessary or desirable in such a construction.

The present invention makes use of a single piece wall plate, a lid provided with integral arms carrying integral hinge pins which are adapted to cooperate with spaced notches in the top of an integral raised portion on the wall plate, a helical spring for surrounding one of the pins and a pressed sheet metal cover which completes the hinge construction, covers the spring and is secured to the wall plate by parts integral with the cooperating units.

As shown in Fig. 1 of the drawing, the wall plate 15 is rectangular and in the single gang form shown is of conventional size for closing the open face of the usual switch box, across the face of which is mounted a conventional form of convenience outlet, that for the plate illustrated being of the dual type and provided with two slotted faces each arranged to receive the prongs of a standard attachment plug. The plate 15 is hence provided with a pair of openings 16 properly positioned to each expose one of the faces of the convenience outlet therethrough when the plate is mounted by means of a central mounting screw passing through the opening 17 therein and received into a threaded hole in the convenience outlet fitting. Any suitable form of gasket (not shown) may serve to seal the plate 15 against the forward edges of the mounting box.

The plate 15 is of conventional rectangular shape and of standard dimensions. Preferably, however, it is not a thin, pressed metal plate but a relatively heavy one cast of some light metal such as aluminum. This construction permits certain integral portions to be raised above the normal face or flat surface thereof, such as the elliptical rim 18 surrounding both openings 16, and also the pair of blocks 19, one adjacent each plate opening 16 for purposes which will subsequently appear. The back of the plate as illustrated in Fig. 10 includes a shallow recess 20 formed by the rearwardly extending rim 21 which enables better contact with a flexible gasket. The recesses 22 shown one adjacent each of the openings 16 are to accommodate the heads of the screws and the ends of the mounting straps of the convenience outlet which project above the edges of the wall thereof.

Each opening 16 is surrounded on the front face by a forwardly protruding lip 23 whereby the resilient gasket 24 carried on a hinged cover or lid 25 may engage it tightly to preserve watertightness. There is a lid 25 for each opening 16 and the lids are individually hinged to the blocks 19 in a manner which will now be described. Each lid carries on its inner face an integral

circular rim 26 about which the gasket 24 is fitted. These lids, like the plate itself, are individual castings of light metal in order that the hinge mechanism may be integrated therewith.

In order to provide hinge parts on each lid extensions 27 and 28 project beyond the upper edge of the lid, one on either side and the facing walls of these extensions are fitted with aligned, integral pivot pins 29 and 30, the one on the left projection being relatively short and intended solely for use as a pivot, whereas the one on the right extension is about twice the length of 29 and is intended to hold the helical spring 32, which serves to maintain the closing tension on the lid, and has the end portion to act as a pivot in cooperation with the part 29.

The facing ends of these pivot pins are spaced apart as clearly seen in Fig. 8, and are adapted to be received individually in the spaced half cylindrical notches 33 and 34 in one of the blocks 19. These notches are illustrated best in Figs. 2 and 3 and the pins are shown seated therein in Fig. 8. The blocks 19 are integral with the plate and with rim 18 thereon, and their top surfaces 35 are flat and parallel to the surface of the plate.

In addition to pivot sockets 33 and 34 is a deep slot 37 through each block 19 closely adjacent to the opening 16 for a purpose which will shortly appear. In addition block 19 has an extension 40 beyond the upper edge of the plate, as clearly seen in Figs. 2 and 3, and this is provided with laterally extending wings 41 and 42 by virtue of the deep slots 43 and 44 between them and the main body on the block. These slots 43 and 44 as well as the recess 37, as seen in Fig. 3, taper, because they have been formed by core or die portions which have the necessary draft.

As seen in Fig. 8 and several of the other figures, the pin 30 on the lid is surrounded for a part of its length by the several turns of helical spring 32 and one end, 46, of this spring rests in notch 47 alongside of the upwardly projecting lip 48 at the upper edge of the cover plate 25 between arms 27 and 28. As viewed in Fig. 9 the wire extending from arm 46 passes down under the pivot pin 30, makes several convolutions thereabout and terminates in tangent arm 49 passing under extension wing 42 and between it and chamfer 50 formed about the outer periphery of plate 15. This is best seen in Fig. 9. It will be seen that arm 49 is rigidly held between 42 and 50 after the coils of the spring have been stressed sufficiently to hold the lid closed.

As viewed in Fig. 9 the convolutions of the spring are seen to be wound about pivot pin 30 in the counter-clockwise direction from arm 46 for approximately four turns and then arm 49 extends outwardly tangentially thereto and passes between the chamfer on the edge of wall plate 15 and the arm 42. The spring when in the condition just described and illustrated is under considerable tension so that it exerts a rotational effort toward closing the lid 25 against its gasket to insure watertightness.

To maintain the assemblage just described in the proper relationship, it is enclosed in a pressed sheet metal cover 60, best seen in perspective in Fig. 7. This has a semi-cylindrical portion 61 adapted to encase the upper half of spring 32 and engage its outer convolutions to prevent pivot 30 from moving upwardly out of its socket. To the left of this portion the top of this cover is flattened as at 62 so that its under surface engages against the top surface of pivot pin 29, as best seen in Figs. 4 and 5, acting thus to hold it closely into its socket. The forward or lower side of the cover is provided with a pair of tangs 62 and 63 the first of which is received in the deep notch 37 shown in Figs. 2 and 3 and the second, spaced laterally to the right thereof, passes down closely against the edge 64 of the block 19 and its front face lies against the flat surface 65 (Fig. 2). On the far side of the cover are two depending tangs 67 and 68 spaced

apart the same distance as that between the bottoms of the notches 43 and 44 into which they fit, as seen best in Fig. 5.

To hold the assembly of wall plate, lid, spring and cover as a unit, the lower ends of the downwardly projecting arms 67 and 68 are pinched or bent toward each other, as best shown in Fig. 6, and thus engage beneath the metal of the neck between the notches 43 and 44 and prevent any relative movement of the cover in respect to the plate. This makes the cover a rigid part of the assembly and since its length is just adequate for it to fit between the arms 27 and 28 of the hinge plate 25 a portion of this cover can be extended as at 70 to provide shoulder 71 to be engaged by the arm 27 when the cover is opened a substantial amount beyond 90° to act as a limit stop. The right hand cover in Fig. 1 is lifted substantially to its maximum and this view, as well as Figs. 4 and 5, illustrates the turned up tab or tongue 73 at the lower end of the lid which facilitates engagement by the finger or thumb for lifting.

Since the gasket 24 is integrated with the lid 25 by a suitable adhesive and centered by means of the upstanding ridge 26 the whole assembly of parts just described is an integral whole held together solely by the bending inward of the ends of the tangs 67 and 68. No other fastening means are necessary and hence there are no loose pins, screws, rivets or other parts used in the assembly. The hinge construction provided is strong, accurately made to prevent wobbling or lateral movement of the lid and easily constructed by die casting of the several parts without the requirement for any machining whatsoever, the sheet metal cover 60 of course being made in a die stamping operation.

I claim:

1. In a waterproof wall plate assembly for an electric convenience outlet, in combination, a metal wall plate for covering the face of an outlet box and having an access opening therethrough for exposing a convenience outlet in the box to receive an attachment plug, a lid for said opening comprising a rigid plate having a pair of substantially parallel spaced arms extending beyond one end thereof, aligned pivot pins extending toward each other, one from each arm and having their facing ends separated a fixed distance, a block integral with said plate and extending above the top surface thereof adjacent said opening, the top surface of said block being flat and parallel to the plate top surface, aligned, half cylindrical notches in said block spaced said fixed distance to receive and act as bearings for said pivot pins, a cover for said block shaped to hold said pins in said notches and interengaging integral parts on the block and cover exposed beyond one edge of the plate for securing the cover to the block.

2. The wall plate assembly of claim 1 in which a helical spring surrounds one of said pivot pins between its arm and notch, said spring having extending end wires one engaging the plate and the other the lid to exert a closing force on said lid.

3. The wall plate assembly of claim 1 in which the upper surface of the lid is substantially coplanar with the upper surface of said block, said arms substantially covering the ends of said block and said lid having an upwardly directed extension between said arms overlapping the top surface of said block and extending to the said cover.

4. A hinge construction for a lid protecting a convenience outlet adapted to be exposed through a hole in an outlet box wall plate comprising in combination a block extending integrally above the front surface of said plate adjacent said hole, a pair of parallel arms extending from the side edges of said lid to encompass said block, aligned pivot pins extending toward each other from said arms, notches in said block spaced to pivot said pins and resist axial movement thereof, one of said pins being longer than its notch and receiving a helical spring having its opposite ends flexed respectively against said plate and lid to urge the latter toward closed position, and a

cover for said spring and pivot pins secured to said block and shaped to engage one pivot pin and the periphery of the spring on the other to hold the lid assembled on the plate.

5. The hinge construction of claim 4 in which said block has vertical channels in the ends thereof remote from the lid, and tangs on the edge of said cover remote from the lid extending through said channels and deflected beyond the channel bottoms.

6. The hinge construction of claim 5 in which said block has a vertical passage therein on the lid side of the hinge axis and a tab extending into said hole from the edge of said cover adjacent said lid.

7. A hinge for a lid for an aperture in a wall plate for an outlet box comprising, in combination, an integral extension above the surface of said plate adjacent said aperture and having two aligned, spaced, semicylindrical notches therein with their axis parallel to the plate surface and spaced from an edge of the hole, a lid for said hole having spaced arms extending therefrom, aligned pivots extending toward each other one from each arm and spaced to the order of the said notch spacing, a cover for said extension and said pivots adapted to cooperate

10
15
20

with the latter to hold them in said notches, and spaced tangs on said cover straddling a portion of said extension and bent beneath it to hold the assembly together.

8. The hinge as defined in claim 7 in which one of said pivots is longer than its notch, a helical spring surrounding the excess length of said pivot and having end wires respectively engaging the plate and the lid to bias the latter toward aperture closing.

9. The hinge as defined in claim 7 in which said pivots are substantially cylindrical and their axis lies substantially in the plane of the upper surface of the lid.

10. The hinge as defined in claim 7 in which a stop surface is provided by extending one end of the said cover above one of the tangs thereon and the lid arm adjacent to said end is positioned to engage said extension upon opening movement in excess of 90° to limit the degree to which the lid may be lifted.
